MAURY W. HIBBARD, OF CHICAGO, ILLINOIS.

FLUID-PRESSURE BRAKE.

No. 802 285.

Specification of Letters Patent.

Patented Oct. 17, 1905.

Application filed November 2, 1903. Serial No. 179,445

To all whom it may concern:

Be it known that I, MAURY W. HIBBARD, a citizen of the United States, residing at Chicago, in the county of Cook and State of Illinois, have invented a new and useful Improvement in Fluid-Pressure Brakes, of which the following is a specification.

This invention relates to improvement in the quick-action triple valves of automatic 10 air-brake systems for railway-trains.

It is in the nature of an improvement upon the construction of the triple valve shown, described, and claimed in a separate concurrent application for Letters Patent filed by me July 15 6, 1903, Serial No. 164,324.

My objects are to provide means for protecting the valve-actuating flexible diaphragms against undue strain in use, to provide a novel diaphragm-actuated slide-valve governing 20 the brake-cylinder exhaust-passage, the diaphragm itself operating at the same time to control the feed to the auxiliary reservoir, and, further, to provide other improvements which tend to render the construction particularly 25 compact, durable, and well adapted for its purpose.

In the accompanying drawings I show my improved valve device in section, fastened in the usual manner against the end of an auxiliary reservoir, the latter and the pipe extending to the brake-cylinder being also shown in section and broken away.

A is the triple-valve body, and BC caps secured thereto, all of which make up the shell 35 of the valve device. The shell has the train-pipe port or passage a, port or chamber b, registering with the brake-cylinder pipe D, and ports c d for communication with the auxiliary reservoir E.

F is a piston-chamber having the bushing e and closed by the chambered cap B, presenting a shoulder or annular piston-seat f.

A chamber G is in open communication at one side with the passage d and is separated 45 from the chamber F by a wall g, having a central opening through it, formed with an annular valve-seat g'.

H is an emergency-passage extending from the chamber F, where it presents ports h, near 50 the seat f, to the brake-cylinder passage or chamber b. Around the opening between the passages H and b is a bushing i, presenting a valve-seat, and in line therewith is an opening between the passage H and chamber G, 55 presenting an annular valve-seat k.

I is a piston device having a back plate l,

the periphery of which slides freely in the bushing e. Fastened to the back plate is a forward plate or disk m, having a central opening m' and presenting a central pocket 60 around said opening to receive the end of a graduating spring K, bearing at its opposite end against the cap B.

L is a cylindrical cup-shaped valve sliding in the opening between the chamber G and 65 passage H and formed with a valve-face i', fitting the valve-seat i, and with a valve-face k', fitting the valve-seat k. In the end of the cylindrical valve L is a central service-port n, surrounded by a flaring valve-seat n', and adjacent thereto is an inner enlargement in the cylindrical valve, presenting a shoulder n².

On the back plate l of the piston-valve device I is a hollow extension presenting an annular valve-face l', fitting the seat g', and extending therefrom is a hollow stem I', constructed, as shown, with longitudinally-extending slots l² and presenting a straight annular portion l³ to slide in the hollow valve L and an enlarged head portion l⁴, movable 80 in the enlarged part of said valve to engage the shoulder n², as hereinafter described. Confined at its annular edge portion between the parts l and m of the piston-valve device I is a flexible preferably thin metal disk M, 85 having a central opening through which passes a threaded plug p. Fastened against the plug p is a hollow stem p', presenting an inner shoulder p² and a reduced straight cylindrical part p³, fitting and sliding through the 90 part l³ of the stem I'.

N is a graduating-valve seating at its end against the valve-seat n'. The valve N slides in the guide formed by the part p³ and has an annular head portion N' in the part p', arranged to contact with the shoulder p². In the part p' is a light cushioning-spring N², 95 confined between the valve N and plug p.

On the stem I' is an annular shoulder l⁵, and confined between the said shoulder and 100 the inner end of the valve L is a light valve-seating spring l².

The graduating-spring K operates to press the piston-valve device in the backward direction, whereby the valve l³ closes the valve-seat or port g'. The spring k² tends to press the valve L against the seat k' and seat or emergency-port i', and the spring N² tends to press the graduating-valve N against the seat n' to close the service-port n. The cushioning-spring N² removes the necessity of a rigid connection between the valve N and

diaphragm, which would make it necessary to employ great care in distancing the seating-faces of the two. The face of the back portion l presents a bearing-surface l^1 for the flexible diaphragm M , permitting the latter to withstand any amount of pressure against it from the train-pipe side without danger of strain. The disk m is shaped on its rear side to present a bearing-surface m^2 for the face of the plug p and the entire surface of the diaphragm M when the latter is forced in the forward direction by pressure from the auxiliary reservoir, as hereinafter explained. Thus all danger of undue strain upon the flexible diaphragm M is removed.

In the upper part of the body A is a chamber P , closed by the cap C . Confined between the body A and cap C is a slightly-dished stiff-metal disk q , having a central opening q' . In the under surface of the cap C is a central socket or chamber C' , from which extends a cored passage r to the piston-chamber F . The passage r extends through the bushing e , opening into the chamber F at the port r' in the position shown. Confined around its annular edge portion between the cap C and disk q is a flexible preferably thin metal diaphragm Q , having a central opening, to which is secured a stem Q' , having a recessed downward-extending arm or hook portion Q^2 . In the bushing e in the position shown is a port e' , extending to a valve-chamber R between the chambers F and P . In the chamber R at the port e' is a valve-seat e^2 , and at the lower end of the passage s , extending from the chamber R to the chamber P , is a valve-seat s' . In the chamber R is a puppet-valve R' , seating normally against the valve-seat e^2 , and in the passage s is a puppet-valve R^2 , seating in the chamber R normally upward against the valve-seat s' . Confined between the valves R' and R^2 is a light spring R^3 . The valve R^2 has a stem R^4 projecting upward into the chamber P .

On the body A , where it fits against the opening E' of the auxiliary reservoir, is a valve-face t , through which extend the port d , a port t' , communicating with the brake-cylinder passage-chamber b , and a port t^2 , communicating with the exhaust chamber or passage S . The ports d t' t^2 are in vertical line.

T is a slide-valve fitting and sliding upon the seat t and having the chamber v and a passage through it, v' , in the relative positions shown. The slide-valve is held to its seat by the spring T' , the spring in turn pressing and sliding against a stiff plate T^2 , forming part of the body A , or fastened independently to the auxiliary reservoir.

In the chamber P is a pivot-pin w , on which is fulcrumed a lever v , extending at one of its arms through the opening c and at its other arm passing through the recess in the arm or hook Q^2 and over the path of the stem R^4 of the valve R^2 .

Beyond the opening c the lever V is pivot-

ally connected, by means of a link V' , to the slide-valve T .

In practice air from the train-pipe enters through the port a , passing through the strainer a' across the drain-cup B' to the chamber F , supplementing the action of the graduating-spring K in pressing the piston-valve I against the seat g' and operating to press the diaphragm M to the seat l^1 to move the parts carried thereby to the backward position, wherein the graduating-valve N is pressed to its seat by the spring N^2 . The train-pipe pressure also passes freely through the port r' and passage r to the chamber C' to bear against the upper surface of the diaphragm Q . As the chamber P is always in open communication with the auxiliary reservoir through the port c , the under side of the diaphragm Q is subject to all variations of reservoir-pressure. When the latter is below the pressure of the train-pipe, the diaphragm Q will be forced downward by the train-pipe pressure, causing the lever V at its free end to bear downward upon the valve-stem R^4 and open the valve R^2 . This permits pressure from the chamber F to open the valve R' and pass through the port e' , chamber R , and port s to the chamber P and auxiliary reservoir to feed the latter. In the position shown the slide-valve T closes communication between the chamber G and auxiliary reservoir and closes communication between the ports t' t^2 of the exhaust-passage. Thus in the event that the graduating-valve N does not seat perfectly or should open before movement of the diaphragm Q pressure cannot pass from the auxiliary reservoir to the brake-cylinder until the exhaust-valve is closed. When the pressure between the train-pipe and auxiliary reservoir balances, the flexible diaphragm Q may assume the central position shown, the lever V being out of contact with the stem of the valve R^2 , and the latter is closed by its spring R^3 . When train-pipe pressure is reduced for a service stop, the then preponderating auxiliary-reservoir pressure raises the diaphragm Q against the seat x , presented by the cap C . This seat properly limits the rise of the diaphragm and relieves the latter from strain, just as the surface q^2 of the plate q relieves the diaphragm from undue strain when pressed in the downward direction. Rise of the diaphragm Q against the seat x causes the lever V to move the slide-valve in the downward direction, closing or maintaining closed communication between the ports t' t^2 of the exhaust-passage and opening the port d , whereby the chamber G is opened to the auxiliary reservoir. This reservoir-pressure, being in excess of the reduced train-pipe pressure, causes the diaphragm M to be moved from its seat l^1 . In this movement the stem p' p^3 is drawn forward, causing the shoulder p^2 to engage the head N' of the valve N and withdraw the latter from its seat n' . Pres-

sure from the auxiliary reservoir through the chamber G will then pass through the slots t^2 of the stem I' to the service-port n and brake-cylinder, producing service application of the brakes. When train-pipe pressure is raised to release brakes, the diaphragm Q, as before stated, is lowered to cause the lever D to raise the slide-valve to bring about communication between the exhaust-passage ports t' t^2 , where-
10 by the air in the brake-cylinder exhausts freely. Following the opening of the exhaust the lever V opens the valve R² to bring about feeding of the auxiliary reservoir. Thus it will be seen that the exhaust will be opened
15 before the feed of the auxiliary reservoir commences. When pressure is reduced in the train-pipe to bring about an emergency stop, the operation of the diaphragm Q is the same as in the case of a service stop, but naturally
20 quicker. The sudden great preponderance of auxiliary-reservoir pressure causes the dia- phragm M to be first moved to open the service-port n and then the whole piston device to be moved from the seat g' without the re-
25 sistance of the emergency-valve to expose the full area of the piston device to auxiliary-reservoir pressure, which overcomes the resistance to movement of the emergency-valve and moves the piston device to the seat f .
30 The first result of this movement is to slide the head portion of the stem t^4 against the shoulder n^2 to engage the valve L and to then move the valve L from its seat to open the emergency-port i . Before the piston device
35 reaches the seat f there will be a sudden rush of pressure through the ports h and the emergency-passage H from the train-pipe to the brake-cylinder to effect the serial quick ac-
40 tion. When the piston device reaches the seat f , its rear edge uncovers the ports h suf- ficiently to permit the auxiliary-reservoir pressure passing through the chamber G and port g' to rush through the emergency-pas-
45 sage H to the brake-cylinder in the required time. Thus it will be seen that my improved valve device is arranged to produce the aux-
iliary-reservoir feeding, service stops, and emergency stops in the manner required by the rules of the Master Car-Builders' Asso-
50 ciation and performs the said functions with great rapidity and certainty. The construc-
tion of the piston-valve device, involving the springs N^2 k^2 , insures thorough and proper seating of all the valves carried thereby. The
55 construction involving the diaphragm Q, lever P, and slide-valve T and attendant parts is particularly responsive to the variations in pressure between the train-pipe and auxiliary reservoir and certain in its action.
60 My improved valve device is of a particu- larly compact, durable, and inexpensive con-
struction, and while I prefer to provide it throughout as shown and described various modifications of details within the spirit of

the invention as defined by the claims may be made.

What I claim as new, and desire to secure by Letters Patent, is—

1. In an automatic fluid-pressure brake apparatus having an abutment, movable to open and close the passage for pressure to the brake-cylinder, a valved passage for feeding pressure from the train-pipe to the auxiliary reservoir, and a brake-cylinder exhaust-passage, the combination of a separate movable flexible diaphragm exposed on opposite sides to pressure from the train-pipe and auxiliary reservoir respectively, and a slide-valve govern-
75 ing said exhaust-passage actuated by move-
ment of said flexible diaphragm, under varia-
tions of pressure, to open and close said ex-
haust-passage.

2. In an automatic fluid-pressure brake apparatus having an abutment, movable to open and close the passage for pressure to the brake-cylinder, a valved passage for feeding pressure from the train-pipe to the auxiliary reservoir, and a brake-cylinder exhaust-passage, the combination of a separate movable flexible diaphragm, exposed on opposite sides to pressure from the train-pipe and auxiliary reservoir respectively, and a slide-valve, gov-
erning said exhaust-passage and the passage of pressure from the auxiliary reservoir to the brake-cylinder, actuated by movement of said flexible diaphragm under variations of pres-
sure to open and close said passages.

3. In an automatic fluid-pressure brake apparatus having an abutment, movable to open and close the passage for pressure to the brake-cylinder, a valved passage for feeding pressure from the train-pipe to the auxiliary reservoir, and a brake-cylinder exhaust-passage, the combination of a separate movable flexible diaphragm, exposed on opposite sides to pressure from the train-pipe and auxiliary reservoir respectively, a slide-valve govern-
100 ing said exhaust-passage, and an operating-
lever for the slide-valve actuated by move-
ment of said flexible diaphragm.

4. In an automatic fluid-pressure brake apparatus having an abutment, movable to open and close the passage for pressure to the brake-cylinder, an auxiliary reservoir-passage for feeding pressure from the train-pipe to the auxiliary reservoir, and a brake-cylinder ex-
haust-passage, the combination of a separate movable flexible diaphragm exposed on oppo-
site sides to pressure from the train-pipe and auxiliary reservoir respectively, a slide-valve govern-
115 ing said exhaust-passage, an operating-
lever for the slide-valve actuated by move-
ment of said flexible diaphragm, and a check-
valve in the said auxiliary-reservoir passage
120 in the path of said lever, substantially as and
for the purpose set forth.

5. The combination with a valve, of a mov-
able valve-actuating flexible diaphragm, a sup-

- porting-casing therefor having a wall limiting the movement of the diaphragm in the direction of effecting closing movement of the valve and against which the diaphragm seats, under 5 pressure, to be relieved thereby from undue strain, and means coöperating with the diaphragm and valve for permitting the diaphragm to move to its seat after the valve is closed.
- 10 6. The combination with a valve, of a movable valve-actuating flexible diaphragm, a supporting-casing therefor having walls at opposite sides of the diaphragm limiting the movement of the diaphragm under pressure from 15 either direction to relieve the diaphragm from undue strain, and means coöperating with the diaphragm and valve for permitting the diaphragm to move to one said wall in opening the valve and to the other said wall after the 20 valve is closed.
7. In an automatic fluid-pressure brake apparatus having ports and passages communicating respectively with the train-pipe, auxiliary reservoir and brake-cylinder, the combination 25 of an emergency-valve, a piston device governing said valve, a valve-seating spring interposed between said piston device and valve, a graduating-valve and a flexible diaphragm on said piston device and having movement

independent thereof operatively connected 30 with said graduating-valve, said piston and diaphragm being exposed on opposite sides to pressure from the train-pipe and auxiliary reservoir respectively.

8. In an automatic fluid-pressure brake apparatus, having ports and passages communicating respectively with the train-pipe, auxiliary reservoir and brake-cylinder, the combination of a chambered emergency-valve provided with a service-port, a piston device having a chambered perforate stem operatively engaging said emergency-valve, a diaphragm on said piston device and having movement independent thereof, a graduating-valve in the chambered emergency-valve governing 40 45 said service-port, and in the path of said diaphragm to be opened by movement thereof in one direction, and a cushioning-spring interposed between the said diaphragm and graduating-valve, the said piston device and diaphragm being exposed on opposite sides to pressure from the train-pipe and auxiliary reservoir, respectively.

MAURY W. HIBBARD.
